UNITED STATES PATENT OFFICE.

ROBERT ELMER LAW, OF SCIO, OHIO.

SUPERHEATER FOR STEAM-ENGINES.

SPECIFICATION forming part of Letters Patent No. 738,618, dated September 8, 1903.

Application filed March 20, 1903. Serial No. 148,744. (No model.)

To all whom it may concern:

Be it known that I, ROBERT ELMER LAW, a citizen of the United States, residing at Scio, in the county of Harrison and State of Ohio, have invented a new and useful Superheater for Steam-Engines, of which the following is a specification.

This invention relates to certain improvements in steam-engines, and particularly to steam-engines of that class employed for traction purposes or for operating agricultural or other machinery where the engine is constantly in the open air and where in cold weather considerable loss results from condensation of the steam in its passage from the boiler to the cylinder or cylinders of the engine.

One of the principal objects of the invention is to provide a means for preventing un-
due condensation of the steam and the loss
of power due to cooling of the steam and its
consequent reduction in pressure while pass-
ing from the boiler to the engine.

A further object of the invention is to pro-
vide a simple and economical device whereby
loss from condensation due to the cooling of
the steam-supply pipe or the cylinder may be
prevented without any considerable loss of
energy of the exhaust-steam at the stack
when the exhaust is used for the purpose of
creating or augmenting the draft.

With these and other objects in view the invention consists in the novel construction and arrangement of parts hereinafter de-
scribed, illustrated in the accompanying draw-
ings, and particularly pointed out in the ap-
pended claims, it being understood that va-
rious changes in the form, proportions, size,
and minor details of the structure may be
made without departing from the spirit or
sacrificing any of the advantages of the in-
vention.

In the accompanying drawings, Figure 1 is a longitudinal sectional elevation of a portion of a steam-engine, in this case an ordinary form of traction-engine, illustrating the application of my invention thereto. Fig. 2 is a transverse sectional elevation on the line 2 2 of Fig. 1. Fig. 3 is a similar view through the steam-chest and cylinder of the engine, showing the steam-jacket surrounding the two.

Similar numerals of reference are employed to indicate corresponding parts throughout the several figures of the drawings.

In the drawings, 1 indicates the forward end of a cylindrical boiler which may form a part of a traction or other engine, the forward flue-sheet being shown at 2 and this flue-
sheet serving to separate the boiler proper 60 from the smoke-box 3. From the upper end of the smoke-box leads a stack 4, which may be of any ordinary construction. In engines of this general class the cylinder or cylinders are secured to the boiler or its supporting-
frame generally at a point adjacent to the forward end of the boiler, and in the drawings 5 indicates a cylinder forming a part of a steam-engine to which power is supplied from the boiler, said cylinder being provided with 70 a suitable piston and connected in the usual manner to a cranked shaft from which power may be transmitted for any purpose, and in this connection it is to be observed that the particular form of boiler or engine forms no 75 part of the present invention, as the invention is equally applicable to locomotives or sta-
tionary engines, as well as to those employed for traction, hoisting, and other purposes.

The cylinder is provided with a plurality 80 of peripherally-disposed lugs 7, to which is secured a jacket 8, or the jacket may form an integral part of the cylinder and cast in the usual manner by the introduction of suit-
able cores between the outer face of the cyl-
inder and the inner wall of the jacket. To 85 one side of the cylinder is bolted or otherwise secured a steam-chest 9, having a slide or other form of valve 10, which receives motion in the usual manner from an operative part 90 of the engine, and surrounding said steam-
chest is a jacket 11 in communication with the jacket surrounding the cylinder, and at one of the ends of the cylinder is an auxiliary head spaced from the cylinder-head and forming a space in communication with the cylin-
der-jacket. The spaces thus formed around the cylinder and its head and around the steam-chest are all in communication with each other, and at the steam-chest these spaces 100 are placed in communication with the ex-
haust-port, controlled by the valve, so that all of the exhaust-steam from the engine is led through the spaces around the steam-

chest and cylinder, maintaining the temperature of these portions of the engine when exposed to low temperature.

The main steam-supply pipe 15 has an inlet-opening at or near the upper end of the steam-dome 16 and is thence led forwardly through the upper portion of the boiler and extends through the flue-sheet into the smoke-box, being thence extended upwardly and rearwardly to a valve 18 and valve-casing 19, in which is an ordinary form of throttle-valve, controlled by a governor 20. The steam thence passes directly to the chest, and its action is governed entirely by the slide-valve in the usual manner.

The live-steam pipe passes through a cylindrical casing or tube 22, which forms the exhaust, and is connected at one end to the upper portion of the steam-chest, being in communication with the jacket surrounding the chest and being provided with suitable bolting-flanges, as indicated at 23, whereby it may be secured to the steam-chest jacket. The exhaust-pipe is of somewhat larger diameter than the live-steam pipe and leads directly down through the shell of the boiler into the smoke-box, where it terminates in an upwardly-directed nozzle 24, located under the smoke-stack, so that the exhaust-steam may operate in the usual manner to augment the draft of the boiler.

By placing the steam-exhaust pipe around the live-steam pipe the heat of the live steam is retained and all condensation and reduction in pressure due to exposure of the live-steam pipe to the open air is prevented. In cold weather the loss due to the cooling of the cylinder and steam-chest considerably reduces the power of the engine, the metal absorbing considerable heat from the steam at each stroke of the engine, and this being conducted by radiation to the air, so that loss of heat results at each stroke of the engine. By surrounding both the steam-chest and the cylinder with a jacket for the passage of the exhaust-steam and by covering and inclosing the live-steam pipe from the point where it emerges from the smoke-box this loss and condensation is prevented, while no back pressure results and the value of the exhaust-

steam as a draft-producing agent is not materially affected.

Having thus described the invention, what is claimed is—

1. The combination with a boiler having a smoke-box divided from the steam-space by a flue-sheet, of a stack, an upwardly-directed steam-discharge nozzle arranged in the smoke-box in alinement with the stack, a steam-engine, a jacket surrounding both the cylinder and steam-chest of the engine, a port leading to the jacket, communication between the engine-exhaust and the jacket being governed by the valve of said engine, an exhaust-pipe in communication with the jacket and leading through the shell of the boiler to the smoke-box, said steam-pipe communicating with the nozzle, and a live-steam pipe extending from the steam-space through the flue-sheet of the boiler into the smoke-box and thence passing through the exhaust-pipe to the steam-pipe of the engine, substantially as specified.

2. The combination with a boiler having a forward smoke box and stack, of a steam-engine supported by the boiler and including a cylinder, a steam-chest and valve, a cylinder-jacket formed integral with the cylinder, a steam-chest jacket integral in part with the steam-chest and cylinder, a removable jacket member forming one wall of the steam-chest, a live-steam pipe extending from the dome of the boiler through the forward flue-sheet and thence through the smoke-box and to the steam-chest, ports controlled by the valve for placing the cylinder exhaust-port in communication with the jackets, and an exhaust-pipe leading from the jackets to the smoke-box, said exhaust-pipe surrounding the live-steam pipe and having a terminal upwardly-directed nozzle in alinement with the smoke-stack.

In testimony that I claim the foregoing as my own I have hereto affixed my signature in the presence of two witnesses.

ROBERT ELMER LAW.
